DISHWASHING MACHINE

Tord Erik Daniel Bilde, Stockholm, Sweden, assignor to Bolinders Fabriks Aktiebolag, Stockholm, Sweden, a corporation of Sweden

Application April 2, 1936, Serial No. 72,432
In Sweden April 8, 1935

12 Claims. (Cl. 141—9)

My present invention relates to dishwashing machines.

The principal object of my invention is to provide a dishwashing machine which has an effective washing and rinsing action, low water consumption and low power consumption, large useful volume, and which is silent in operation and simple and reliable in construction as well as easy to handle so as to be useful especially for domestic purposes.

A further object of my invention is to provide a dishwashing machine of the type described which is of compact design and of small dimensions, especially of low height, this being at advantage when using the machine in kitchens of limited space.

Another object of my invention is to provide a dishwashing machine having two spraying systems, one for washing liquid and the other for rinsing liquid, which systems are entirely separated from each other and arranged mainly within a lower casing of the machine.

Further objects of my invention will be apparent according as the following description proceeds reference being had to the accompanying drawing showing by way of example a preferred embodiment of my new machine.

In the drawing:

Fig. 1 is a vertical sectional view of the machine.

Fig. 2 is a plan view of the lower casing of the machine.

Fig. 3 is a sectional view along the line III—III in Fig. 1.

Figs. 4 and 5 show modifications.

The lower machine casing 3 has adjustable feet 2 and encloses two liquid tanks 4 and 5, of which one 5 for rinsing liquid encloses on three sides the other 4 for washing liquid. Tank 5 is entirely closed at its top and provided with a filling opening, not shown, whereas tank 4 at its top is covered by a removable strainer 6 through which the liquid flows back to said tank 4. Provided in a separate compartment of casing 3 at the front of the machine and at the side of the two tanks 4 and 5 is an electric motor 7 and two pumps, coupled thereto, one 8 for washing liquid and another 9 for rinsing liquid.

The inlet pipe of pump 8 is designated by 10 and the outlet pipe thereof by 11. Connected with the outlet 11 is a spraying device 12 consisting of hollow arms 12a and 12b provided with nozzles 35 through which washing liquid is sprayed from below and upwards towards the dishes in the basket 13. In the embodiment

shown the spraying device 12 is arranged swingably to and fro in a horizontal plane and is, consequently, rotatably connected with the outlet 11 in which it is inserted by means of a hollow stud 14. Further, the spraying device is so arranged as to be capable together with its short rising pipe of being lifted off from the pump outlet in order to facilitate the cleansing of the apparatus.

The spraying device may be set in motion in different manners, either mechanically from the driving motor, or, as in the embodiment shown, hydraulically by utilizing the reaction pressure of a jet issuing from a nozzle 15 and striking a reflecting member 17 which at the end positions 15 of the swinging spraying device is shifted by means of abutments 16 so as to cause reverse of the motion.

The inlet 18 of the pump 9 communicates with the tank 5 for rinsing liquid, whereas its outlet 20 is connected with a pipe system 19, 19a, provided with nozzles 20 for the spraying of the rinsing liquid. The rinsing liquid pipes 19, 19a are rigidly secured to the outlet of the pump 9 and arranged along the outer edges of strainer 25 so as not to prevent the removal of said strainer.

The dish supporting basket 13 rests on supports 21 one of which is shown in Figure 1, and is, preferably, arranged immediately above the spraying members 12.

The washing compartment proper is formed by a cap 22 which is placed on the casing 3 so as to be capable of being lifted off therefrom. In the embodiment shown the cap 22 is placed freely onto the upper edge of the casing 3 which for this purpose is provided with or formed as a supporting flange 23 which is somewhat higher on its outside, so that the cap is guided in its position by said outer flange 23.

The cap 22 may be hinged to the lower casing 3 as shown at 45 in Fig. 4 so that it can be swung outwardly, e. g. towards the back of the machine. In this figure a catch 46 is shown to fix the cap to the lower casing 3 in the closed position of the cap.

According to Fig. 5 a part 47 of the cap 22 is hinged to the lower casing 3 as at 48 so that it can be swung outwards. Part 47 is secured in closed position by a catch 49.

On account of the cap being removable, wholly or in part, the dish supporting basket 13 may be freely removed from and placed on its support in the machine. By this means the manoeuvring of the machine will be simplified, and simultaneously the dishes are easily accessible 55

for inspection without it being necessary first to remove the basket from the machine. Another advantage resides in the fact that the cleansing of the machine will be considerably facilitated, especially when the cap can be entirely lifted off or swung outwards.

Provided in the dishwashing compartment are surfaces arranged and formed in such manner as to deflect towards the dishes jets issuing from the spraying means in order more completely to utilize the washing effect of said jets.

In the embodiment shown there are for this purpose on the roof of the cap 22 provided deflecting surfaces formed by a plate secured inside the roof of the cap and formed with corrugations 32. By these surfaces liquid jets which strike the roof of the cap are deflected in suitable direction towards the dishes in the manner indicated by the arrows in Fig. 1. The roof may at its outer edges be provided with oblique parts 24 which partake in guiding the jets towards the corrugations 32 or form themselves reflecting surfaces.

In operation the washing liquid is circulating in usual manner from tank 4 through pump 8, spraying means 12, washing compartment 22 and through strainer 6 back to tank 4. When the washing operation is completed the spraying means 12 is cut off, whereas pump 9 is rendered operative, rinsing liquid being now pumped from tank 5 to spraying means 19a and over the dishes, the liquid then flowing down into tank 4.

In the embodiment shown the pumps 8 and 9 are driven by a common motor, and in order to simplify the apparatus the pumping wheels of both of the pumps are permanently connected with the motor shaft so as to rotate simultaneously. Preferably, the pumps are so controlled that the pump which is not in operation is shut off from supply of water by means of a flap valve 25, cock or the like, which closes the respective inlet conduit 10 or 18. The flap valves are adjusted by means of rods 26, links or the like which are easily accessible from the outside.

Provided in the tank 4 is a bottom valve 27 having an over-flow 29, said valve being capable of being lifted off or placed on its edge, preferably from the outside, when it is desired to remove the liquid through the outlet 28.

Pump 8 is connected with outlet 28 by a conduit 30 through which washing liquid remaining in the pump is permitted to flow away.

The machine is provided with suitable means for mixing the washing liquid or the rinsing liquid or both with disinfectants and/or fat dissolving agents, e. g. soap. For this purpose one or more containers for such agents are provided within the machine so arranged as to cause the agent to be dissolved and brought along by the circulating liquid.

Inserted in the side wall or roof of the cap 22 is a receptacle 36 containing a disinfectant or a fat dissolving agent, e. g. soap. At its top the receptacle 36 is provided with a slot-shaped opening 37 and at its bottom with a plurality of small holes 38. Further the receptacle 36 contains a control valve in the form of a slotted slide 39 adapted to be rotated from the outside by means of a hand-wheel 40, handle or the like in such manner as to open slot 37 and holes 38 to a greater or less degree or to close them entirely. Soap or a disinfectant either in the form of a solid piece or in form of powder may be placed within the receptacle 36, or said agent may be

used in liquid state, preferably enclosed in a separate drop-bottle. During the operation of the apparatus washing liquid or rinsing liquid enters the receptacle 36 through slot 37, dissolves part of the preparation and flows out through holes 38 intermingled with disinfectant or fat dissolving agent which, consequently, is brought along during the liquid circulation.

The invention is not limited to the embodiment shown in the drawing, nor to the modifications thereof mentioned in the above description. The spraying device may perform a motion other than the reciprocating motion described above. Also other modifications may be conceived without departing from the principle of the invention.

What I claim is:

1. In a dishwashing machine for domestic purposes having a spraying compartment, means for spraying a liquid through a cross-sectional area defined by the side walls of said compartment exclusively from below, said spraying means comprising a sprayer having spray nozzle arranged substantially along lines forming a closed geometrical figure, said sprayer being swingable to and fro in a horizontal plane beneath the spraying compartment around a vertical axis passing substantially through points of the border of said figure and of said area, said figure having a configuration so adapted to the shape of said area that, on the swinging movement of the sprayer from its one end position into its other, said area is sprayed in its entirety.

2. In a dishwashing machine for domestic purposes having a spraying compartment, means for spraying a liquid through a cross-sectional area of said compartment, said spraying means comprising a sprayer having spray nozzles arranged substantially along lines extending from a common point first diverging and then converging, said sprayer being swingable to and fro in a horizontal plane beneath the spraying compartment around a vertical axis passing substantially through said point and through a point of the border of said area, the lines being so adapted to the shape of said area that, on the swinging movement of the sprayer from its one end position into its other, said area is sprayed in its entirety.

3. In a dishwashing machine for domestic purposes having a spraying compartment, means for spraying a liquid through a cross-sectional area of said compartment exclusively from below, said spraying means comprising a sprayer having spray nozzles arranged substantially along two lines extending from a common point first diverging and then converging as well as additional spray nozzles, said sprayer being swingable to and fro in a horizontal plane beneath the spraying compartment around a vertical axis substantially through said point and through a point of the border of said area, said lines and the situation of said additional nozzles being such that, on the swinging movement of the sprayer from its one end position into its other, said area is sprayed in its entirety.

4. In a dishwashing machine for domestic purposes having a spraying compartment, means for spraying a liquid through a rectangular cross-sectional area of said compartment exclusively from below, said spraying means comprising a sprayer having spray nozzles arranged substantially along the sides of a quadrangle as well as additional spray nozzles, said sprayer being swingable to and fro in a horizontal plane be-

neath the spraying compartment around a vertical axis passing through one corner of the quadrangle and through a point substantially at the middle of one side of said rectangular area, the shape of said quadrangle and the situation of said additional spray nozzles being such that, on the swinging movement of the sprayer from its one end position into its other, said area is sprayed in its entirety.

5 10. In a dishwashing machine for domestic purposes having a spraying compartment, means for spraying a liquid through a rectangular cross-sectional area of said compartment exclusively from below, said spraying means comprising a sprayer having spray nozzles arranged substantially along the sides of a quadrangle as well as additional spray nozzles, said sprayer being situated in a horizontal plane beneath said compartment, means at one corner of said quadrangle and 15 in substantially vertical alignment with the middle of one side of said rectangular area for mounting said sprayer for oscillation around a vertical axis through said mounting means, means for imparting to said sprayer a reciprocating motion 20 around said vertical axis, the shape of said quadrangle and the situation of said additional spray nozzles being such that, on the movement of the sprayer from its one end position into its other, said area is sprayed in its entirety.

25 30. 6. In a dishwashing machine for domestic purposes having a spraying compartment, means for spraying a liquid through a rectangular cross-sectional area of said compartment exclusively from below, said spraying means comprising a sprayer having spray nozzles arranged substantially along the sides of a quadrangle as well as additional spray nozzles, said sprayer being swingable to and fro in a horizontal plane beneath the spraying compartment around a vertical axis passing through one corner of the quadrangle and through a point substantially at the middle of one side of said rectangular area, the sides of the quadrangle adjacent said corner being each approximately equal to half the length 35 of said side of the rectangular area and the shape of said quadrangle and the situation of said additional spray nozzles being such that, on the swinging movement of the sprayer from its one end position into its other, said area is sprayed in its entirety.

40 7. In a dishwashing machine for domestic purposes having a spraying compartment, means for spraying a liquid through a rectangular cross-sectional area of said compartment exclusively from below, said spraying means comprising a sprayer having spray nozzles arranged substantially along the sides of a quadrangle and additional spray nozzles arranged within said quadrangle, said sprayer being swingable to and fro in a horizontal plane beneath said compartment around a vertical axis passing through a corner of said quadrangle and through a point substantially at the middle of one side of said rectangular area, the shape of said quadrangle and the situation of said additional spray nozzles being such that, on the swinging movement of the sprayer from its one end position into its other, said area is sprayed in its entirety.

45 75. 8. In a dishwashing machine for domestic purposes having a spraying compartment, means for spraying said compartment with a liquid exclusively from below, said spraying means comprising a sprayer including a spray nozzle pipe bent in the form of a quadrangle and an ad-

ditional spray nozzle pipe extending from a corner of said quadrangular spray pipe inwards of the quadrangle, said sprayer being swingable to and fro in a horizontal plane beneath said spraying compartment around a vertical axis passing through said corner of the quadrangle and situated eccentrically in said spraying compartment.

5 9. In a dishwashing machine for domestic purposes having a spraying compartment, means for spraying a liquid through a rectangular cross-sectional area of said compartment exclusively from below, said spraying means comprising a sprayer including a spray nozzle pipe bent in the form of a quadrangle and an additional spray nozzle pipe extending from a corner of the quadrangle inwards thereof, said sprayer being swingable to and fro in a horizontal plane beneath the spraying compartment around a vertical axis passing through said corner of the quadrangle and through a point substantially at the middle of one side of said rectangular area.

10 15. 10. In a dishwashing machine for domestic purposes having a spraying compartment, means for spraying a liquid through a rectangular cross-sectional area of said compartment exclusively from below, said spraying means comprising a sprayer having spray nozzles along the sides of a quadrangle and additional spray nozzles within said quadrangle, said sprayer being swingable to and fro in a horizontal plane beneath the spraying compartment around a vertical axis passing through a corner of the quadrangle and through a point substantially at the middle of one side of said rectangular area, the shape of the quadrangle being such that the length of the diagonal through said corner is approximately equal to the distance from said point to an opposite corner of said rectangular area.

20 25. 11. In a dishwashing machine for domestic purposes having a casing enclosing a spraying compartment, means for spraying a liquid through a cross-sectional area of said compartment exclusively from below, said spraying means comprising a sprayer having spray nozzles arranged substantially along lines extending from a common point first diverging and then converging, said sprayer being mounted for oscillation in a horizontal plane beneath the spraying compartment around a vertical axis situated eccentrically 30 in the spraying compartment and adjacent a wall of said casing and passing substantially through said point, means automatically to impart to said pipe an oscillatory motion around said axis, said means comprising a movable deflecting member mounted on the pipe in front of a nozzle therein for directing a jet from said nozzle obliquely to the direction of oscillation of the pipe so as to cause the pipe to be moved by the reaction force of said jet, and means on the casing 35 adapted to change the inclination of said deflecting member so as to reverse the direction of oscillation of the pipe at points of the oscillatory path thereof determining an angle of oscillation of the pipe less than 180 degrees.

40 45. 12. In a dishwashing machine for domestic purposes having a casing enclosing a spraying compartment, means for spraying a liquid through a cross-sectional area of said compartment exclusively from below, said spraying means comprising a sprayer including a spray nozzle pipe bent in the form of a quadrangle and an additional spray nozzle pipe extending from a corner of said quadrangular pipe inwards of the quadrangle, said sprayer being mounted for oscillation 50 around a vertical axis passing through said corner of the quadrangle and through a point substantially at the middle of one side of said rectangular area, the shape of the quadrangle being such that the length of the diagonal through said corner is approximately equal to the distance from said point to an opposite corner of said rectangular area.

lation in a horizontal plane beneath the spraying compartment around a vertical axis passing through said corner of the quadrangle and situated eccentrically with regard to said area, means 5 automatically to impart to the sprayer an oscillatory motion around said vertical axis, said means comprising a movable deflecting member mounted on the sprayer at the corner of the quadrangle opposite to the first-mentioned corner in

front of a nozzle therein for directing a jet from said nozzle obliquely to the direction of oscillation of the sprayer so as to cause the sprayer to be moved by the reaction force of said jet, and means on the casing adapted to change the inclination of said reflecting member so as to reverse the direction of oscillation of the sprayer. 5

TORD ERIK DANIEL BILDE.
